Attn:

UNITED STATES PATENT OFFICE.

CHARLES W. RICHARDS, OF SAN FRANCISCO, CALIFORNIA.

FINGER TOOTH-BRUSH.

SPECIFICATION forming part of Letters Patent No. 628,185, dated July 4, 1899.

Application filed December 22, 1898. Serial No. 699,983. (No model.)

To all whom it may concern:

Be it known that I, CHARLES W. RICHARDS, a citizen of the United States, residing in the city and county of San Francisco, State of California, have invented an Improvement in Finger Tooth-Brushes; and I hereby declare the following to be a full, clear, and exact description of the same.

My invention relates to a brush for cleansing the teeth and in a novel construction and mounting of the same.

It consists, essentially, of a tip adapted to fit the finger and having bristles or other like cleansing devices affixed to the exterior end, so that when applied to the finger it may be used for cleansing the teeth.

Referring to the accompanying drawings, Figure 1 is a section through the brush. Fig. 2 shows the application of bristles. Fig. 3 is a detail of a bristle made of celluloid or rubber.

The object of my invention is to provide a convenient device for cleansing the teeth which occupies a small compass when not in use and which may be employed without the disagreeable effects of striking the teeth with the hard handles usually employed for tooth-brushes.

The body or support consists of a tube A of sufficient length and size to be fitted upon a finger of the hand. The tube may be made of rubber, gutta-percha, aluminium, celluloid, or any other suitable or convenient material. As here shown, it is closed at the outer end, so as to form a sort of cot, which fits snugly and closely upon the finger, and the closed end is formed with perforations A' to permit the air within the tube to escape when the tube is placed upon the finger, thereby preventing the formation of an air-cushion within the tube. Upon one side this tube has the surface extended, so as to make an approximately level surface, as shown at a, and upon this surface, which is thickened, as

shown, are fitted the bristles or other like rubbing or cleansing parts B. These bristles, 45 which may be considered to represent any cleansing projections or surfaces, may either be made of the usual materials inserted and secured in the surface a or if made of rubber they consist of a number of small projecting 50 points which serve the same purpose as the bristles. These cleansing-points are preferably longer at the outer end, as shown at b, forming a concave surface to the inner end b', which has slightly less projection than the 55 outer end. These points when made of rubber are preferably cylindrical, and the ends are formed, as shown at b' in the enlarged view, so as to provide converging points, which points will penetrate crevices and 60 indentations between and upon the teeth and thoroughly cleanse the surface.

By applying this device to the finger, which is flexible and easily turned about, all the surfaces of the teeth inside and out can be 65 easily reached, and the teeth are relieved from the uncomfortable shock caused by striking them with the hard handle of the ordinary tooth-brush.

Having thus described my invention, what 70 I claim as new, and desire to secure by Letters Patent, is—

As an article of manufacture, a tooth-brush consisting of a tube or cot adapted to fit the finger, having perforations in its closed end 75 and having one side thickened and flattened, and points projecting from said thickened side and having their outer ends converging to a point.

In witness whereof I have hereunto set my 80 hand.

CHARLES W. RICHARDS.
